CLAIM

The ornamental design for a combined door and storage chest or similar article, as shown.

DESCRIPTION

FIG. 1 is a front perspective view of a combined door and storage chest or similar article showing my new design;

FIG. 2 is a rear perspective view showing a combined door and storage chest or similar article embodying the design of the present invention; and,

FIG. 3 is a bottom plan view thereof.

FIG. 1

FIG. 2

FIG. 3
